DOOR OPERATOR

Frederick William Hall, London, Ontario, Canada,
assignor to Richards-Wilcox Canadian Company, Limited, London, Ontario, Canada

Application June 10, 1938, Serial No. 212,957
In Canada May 23, 1938

5 Claims. (Cl. 268—30)

This invention relates to what are commonly known as canopy doors, that is doors which are pivoted adjacent the top of a door opening and swing from a vertical closed position to a horizontal open position. Such doors are made sometimes in one piece and sometimes are formed with a lower section slideable up and down on the upper part of the door. In Canadian Patent 358,016 such a door is disclosed. In that invention my object was to devise simple means for operating the door which would possess the following characteristics among others:

1. Fast action in opening and closing.
2. A graduated speed both in opening and closing, increasing from zero to a maximum and then decreasing again to zero.
3. Would act as a counterbalance producing an effect which increases as the door swings to the open position.
- 20 I attained my object by means of the constructions which were briefly described as follows.

The upper part of the door structure above the axis of its pivots had a crank shaft journaled thereon provided with crank arms pivotally connected to the upper ends of links which at their lower ends were pivoted on the superstructure of the doorway. The crank shaft was driven by gearing driven by an electric motor, these parts being positioned above the aforesaid axis so that the operating mechanism served as a counterbalance for the door as a whole.

The lower section of the door was actuated by chains secured at their lower ends to said section, which chains passed over sheaves on the upper part of the door, thence under sprocket wheels secured to a shaft journaled on the superstructure, thence round suitable guide sheaves on the building to counterweights which were nearly equal to the weight of the lower door section. An electric motor carried by the superstructure drove the shaft aforesaid, which drove the sprockets and thus the chains to raise the lower door section. The reverse movement was by gravity controlled by the motor. It is found, however, that in modern hangar construction it is sometimes difficult and always inconvenient to find a suitable location for counterweights hanging on the walls, and the swaying of counterweight cables travelling through the superstructure of the building is objectionable.

My object in the present invention is to overcome these objections and this is effected by the constructions which may be briefly described as follows:

On the upper part of the pivoted part of the door structure I mount a hoisting unit which actuates a shaft carrying sprocket wheels which actuate chains which pass round pulleys mounted at the lower end of the upper part of the door and both ends of which chains are secured to the lower part of the door so that by operating the shaft with its sprocket wheels the lower part of the door may be raised and lowered as required.

The invention is hereinafter more fully described and is illustrated in the accompanying drawings in which

Fig. 1 is an inside elevation of the door and part of the doorway superstructure, with the door closed;

Fig. 2 a side elevation of the same, partly broken away; and

Fig. 3 a similar view with the door in the open position.

In the drawings like numerals of reference indicate corresponding parts in the different figures.

Referring to the drawings, 1 indicates part of the frame and superstructure of the doorway. The door itself is formed in two parts, an upper part 2 and a lower part 3. The lower part is provided with rollers 5 adapted to run in the side channels of the door beams 4 which form the back bone of the upper part of the door. At the upper part of the upper part of the door are secured the door pivots 6 which are suitably journaled in the superstructure 1. The upper part of the door extends above the axis of the pivots 6 and is formed of a frame 7 of structural metal. The exposed portions of the door parts may be either solidly panelled, but are preferably partly panelled and partly glazed as indicated in Fig. 1.

Journalled near the top of the upper part 7 of the door is a crank shaft 8, which is provided with the crank arms 9. The ends of these cranks 10, the lower ends of which are pivoted on the superstructure as shown. When the door is substantially vertical the crank and links will be in substantial alignment as shown in Fig. 2. By rotating the crank shaft, however, the links and crank arms may be moved through intermediate stages to occupy the position shown in Fig. 3 when the door is substantially horizontal.

From this construction it follows that the swinging movement of the door either to or from the closed position is at first slow, the rate of movement increasing until the links and crank arms are substantially at right angles to one another, after which the speed of movement

gradually decreases until the final position is reached.

The shaft 8 is driven by spur gearing 13 from the gear ratio reduction unit 12 which, in turn, 5 is driven by the motor 11. All the gearing and the motor, it will be noted, are carried by the upper part of the door itself, thus these parts have a very important function in counterbalancing the door. It will be noted that the position of these parts makes their weight as a 10 counterbalance effective in proportion to the requirements of the varying positions of the door; that is the weight is most effective when it is most required, namely, when the door is fully 15 opened, and the effect of this weight dies away as the door comes into the vertical position where such counterbalance is not required.

The lower part of the door is operable by means 20 of a hoisting unit carried by the superstructure 1 of the upper part of the door. On the superstructure is mounted a motor 20 which, through the medium of a reducing gear 21, operates the shaft 19 journalled on the superstructure. The motor and reducing gear are shown only dia- 25 grammatically and any known constructions may be used for this purpose.

The shaft 19 carries at each end a sprocket wheel 18 adapted to drive the chains 14. Each chain 14 at its lower end passes round an idler 30 15 journalled on the upper part of the door. The ends of the chain are connected respectively to the lug 17 and to the threaded bolt 16 which passes through a lug on the lower door frame and is set up by a nut so that any slack may be 35 taken up as necessary.

From this description it will be seen that no 40 counterbalancing weights are needed and that the lower or sliding door part is operated entirely from the upper or pivoted door part. The operating means for the chains 14 thus assist in 45 the counterbalancing of the weight of the door parts when swung to the position shown in Fig. 3 of the drawings. All the objections to the use of counterbalancing weights are also overcome.

45 What I claim as my invention is:

1. In a swinging door structure, the combination of a doorway superstructure; a door pivoted thereon to swing on a horizontal axis; a lower door section slidably mounted to move up and down on the pivoted door part; a chain connected at opposite ends to the slidable door section; pulleys on the pivoted door part about which the chain passes; and a hoisting unit including a prime mover mounted on and completely supported by the pivoted door part and adapted to drive one of the pulleys to actuate the chain to move the slidable door section, the said unit serving as a counterbalance for the door structure.

60 2. In a swinging door structure, the combination of a doorway superstructure; a door pivoted thereon to swing on a horizontal axis, part of the door extending above the axis; a lower door

section slidably mounted to move up and down on the pivoted door part; a chain connected at opposite ends to the slidable door section; pulleys on the pivoted door part about which the chain passes; and a hoisting unit including a prime 5 mover mounted on and completely supported by the pivoted door part above its axis and adapted to drive one of the pulleys to actuate the chain to move the slidable door section, the said unit serving as a counterbalance for the door structure. 10

3. In a swinging door structure, the combination of a doorway superstructure; a door pivoted thereon to swing on a horizontal axis, part of the door extending above the axis; door actuating mechanism connected with the door and the superstructure including a prime mover mounted on and completely supported by the door; driving means for the actuating mechanism carried by the door above the said axis; a lower door section slidably mounted to move up and down on the pivoted door part; a chain connected at opposite ends to the slidable door section; pulleys on the pivoted door part about which the chain passes; and a hoisting unit including a prime 20 mover mounted on the pivoted door part above its axis and adapted to drive one of the pulleys to actuate the chain to move the slidable door section, the said unit serving as a counterbalance 25 for the door structure. 30

4. In a swinging door structure, the combination of a doorway superstructure; a door pivoted thereon to swing on a horizontal axis; a lower door section slidably mounted to move up and down on the pivoted door part; means connected 35 to the said pivoted door part and lower door section for sliding the latter up and down; and a hoisting unit, including a prime mover mounted on and completely supported by the pivoted door part to actuate the means for sliding the lower 40 door section up and down, the said unit serving as a counterbalance for the door structure.

5. In a swinging door structure, the combination of a doorway superstructure; a door pivoted thereon to swing on a horizontal axis, part of the 45 door extending above the axis; door actuating mechanism connected with the door above the axis and with the superstructure including a prime mover mounted on and completely supported by the door; driving means for the actuating mechanism carried by the door above the said axis; a lower door section slidably mounted to move up and down on the pivoted door part; and means connected to the door part and door section for sliding the latter up and down; a 50 hoisting unit and a prime mover mounted on and completely supported by the pivoted section above its axis to actuate the means for sliding the lower door section up and down, the door actuating mechanism and hoisting unit acting 55 as counterbalances for the door. 60

FREDERICK WILLIAM HALL.
